(No Model.)

H. W. LITTLEFIELD.
FIRE ESCAPE.

No. 288,078.

Patented Nov. 6, 1883.

UNITED STATES PATENT OFFICE.

HENRY W. LITTLEFIELD, OF PHILADELPHIA, PENNSYLVANIA.

FIRE-ESCAPE.

SPECIFICATION forming part of Letters Patent No. 288,078, dated November 6, 1883.

Application filed May 28, 1883. (No model.)

To all whom it may concern:

Be it known that I, HENRY W. LITTLEFIELD, of the city of Philadelphia, county of Philadelphia and State of Pennsylvania, have invented an Improvement in Fire-Escapes, of which the following is a specification.

My invention has reference to fire-escapes, but more particularly to the boxes or receptacles in which they are stored outside of the window; and it consists in a box preferably made of sheet-iron and provided with a hinged top and bottom, the said box being supported upon the outside of the building and in convenient relative position with respect to the window, said top and bottom being hinged and combined with suitable mechanism whereby said top or lid is automatically raised upon allowing the bottom to fall in the act of discharging the fire-escape; further, in providing a fire-escape box having a hinged bottom with suitable mechanism, which, upon raising the window before which said box is located, actuates the latch and allows said bottom to fall and thereby discharge the fire-escape which previously had been supported upon said bottom; and in many details of construction, all of which are fully set forth in the following specification and shown in the accompanying drawings, which form part thereof.

The object of my invention is to provide a suitable storage-box in which to place the fire-escape, and by which, with great facility, the same may be discharged therefrom, the upper part of which is secured in said box, and the lower part extends to the ground, the said discharge taking place automatically upon touching a single lever; also, to so construct the said box that the occupant of the building may step directly from the window into the fire-escape, and in no sense be required to first get into the box before getting upon said fire-escape.

In the drawings, Figure 1 is a sectional elevation of my improved fire-escape, storage box or receptacle, taken on line *x x*. Fig. 2 is a front elevation of same. Fig. 3 is a sectional plan view of same on line *y y*. Fig. 4 is a sectional view of part of same on line *w w*. Fig. 5 is a sectional elevation of a part of same on

line *t t*, and Fig. 6 is a sectional plan view of 50 same on line *s s*.

A is the wall of the building. B is the window. B' is the window-frame. B² is the window-sill. C is the fire-escape box or receptacle, and consists of the light sheet-iron body re-enforced or strengthened at the top by angle-iron F, and at the bottom by angle-iron E. This body is secured to the building by any suitable means—such, for instance, as bolts G G', the upper of which may be provided with eyes g, 60 to which may be secured the fire-escape T, (shown in dotted lines,) and in this instance made to represent what is known as the "Spencer fire-escape." In addition to these bolts the said body may be supported by struts S. 65

K is the bottom, which is made of an angle-iron frame, K', to which is riveted the sheet-iron plate k. This bottom is hinged to the body C close to the inner side, as at L. When pressed up it is caught by a latch, M, pivoted 70 at m, and operated by a toggle-joint, O, the levers of which are pivoted at O' to an angle-iron, O², and the said toggle-joint in its turn is operated by a bell-crank, P', pivoted to the body C at p through the agency of a wire or 75 chain, P. This bell-crank P' may be operated by hand, or more desirably by the window-sash B in the act of raising same. To accomplish this end I provide the window-sash with a plate, Q, which, as it rises, strikes a 80 pivoted lever, P², pivoted to the upper end of bell-crank P', being pressed against a pin or lug, p', by a spring, R, the said pin p' preventing the upward movement of the lever P² without oscillating the bell-crank P'; hence upon 85 raising the sash B the lever P' is oscillated, causing the latch M, through the mediation of the wire P and toggle-joint O, to free the bottom K and allow it to fall. As the window rises farther the arm P² is freed, and the spring 90 M, pressing against the latch M, returns all the latch-operating parts to their normal position.

H is the cover, made inclined, to allow the water to run off, and may be made of sheet-iron h, re-enforced or strengthened upon each side by angle-irons I, which may extend beyond the hinge J, by which the said cover is 95

hinged to the body C at its upper and outer edge, to form cranks or extensions I'.

5 N are wires or chains connecting the bottom K near its hinge, and also the outer ends of the extensions of the cover, and the said wires or chains may pass through slots D' in the body C; and to prevent the passage of water through said slots they may be covered by sliding plates D', sliding in guides d, and supported by said 10 wires or chains, which pass through holes D therein.

The operation is as follows: The bottom K being closed and the top or cover H being open, and the fire-escape T, which may be of 15 any suitable construction, being suitably packed in the receptacle, the lid H may be closed and the window-sash be closed, in which act it presses down the pivoted arm P' without displacing the lever P', and when 20 closed allows it to spring back to its normal position, as shown in Fig. 1. A fire being discovered the sash is raised, and, as hereinbefore explained, the latch M is pressed back, allowing the bottom K to fall, and which in 25 falling pulls upon the wires N, raising the cover or lid H, and simultaneously therewith discharging the fire-escape into an operative position. The person then steps from the window directly into or upon said fire-escape, 30 and without in any manner having to first get into the box, and from that into the fire-escape, which previously had to be pushed or thrown out of the box by manual labor.

While I prefer the construction shown I do 35 limit myself to the same, as my invention may be modified in various ways without in any manner departing from my invention.

Having now described my invention, what I claim as new, and desire to secure by Letters 40 Patent, is—

1. A fire-escape storage box or receptacle provided with a hinged bottom, and latching mechanism to free said bottom and allow it to fall, in combination with a fire-escape for the 45 passage of persons from the building to the ground, adapted to be stored within said box when not in use, and resting wholly upon said bottom, and which, upon allowing the bottom to fall, is automatically discharged into an operative 50 position, reaching from the box to the ground, substantially as and for the purpose specified.

2. A fire-escape storage box or receptacle provided with a hinged bottom opening toward the building, and hinged top or cover opening away from the building, and latching mechanism to free said bottom and allow it to fall, in combination with a fire-escape adapted to be stored within said box when not in use, 60 and which, upon allowing the bottom to fall, is automatically discharged into an operative position, reaching from the box to the ground, substantially as and for the purpose specified.

3. A fire-escape storage box or receptacle 65 provided with a hinged bottom, a hinged top or cover, mechanism to automatically raise

said cover upon allowing the bottom to fall, and latching mechanism to free said bottom and allow it to fall, in combination with a fire-escape adapted to be stored within said box 70 when not in use, and which, upon allowing the bottom to fall, is automatically discharged into an operative position, reaching from the box to the ground, substantially as and for the purpose specified. 75

4. A fire-escape storage box or receptacle provided with a hinged bottom, a hinged top or cover, mechanism to automatically raise said cover upon allowing the bottom to fall, but allow the cover to be raised or lowered 80 without interfering with the bottom when the latter is closed, and latching mechanism to free said bottom and allow it to fall, in combination with a fire-escape adapted to be stored within said box when not in use, and which, 85 upon allowing the bottom to fall, is automatically discharged into an operative position, reaching from the box to the ground, substantially as and for the purpose specified.

5. A fire-escape storage box provided with 90 a hinged top or cover, and a hinged bottom, in combination with mechanism which automatically raises the bottom upon lowering the cover, and a latch to hold said bottom up when raised, substantially as and for the purpose 95 specified.

6. A fire-escape storage box or receptacle provided with a hinged bottom, and latching mechanism to free said bottom and allow it to fall, the said latching mechanism being actuated by raising the window-sash, in combination with a fire-escape adapted to be stored within said box when not in use, and which, 100 upon allowing the bottom to fall, is automatically discharged into an operative position, 105 reaching from the box to the ground, substantially as and for the purpose specified.

7. A fire-escape storage box or receptacle provided with a hinged bottom, a hinged top or cover, mechanism to automatically raise said 110 cover upon allowing the bottom to fall, and latching mechanism to free said bottom and allow it to fall, the said latching mechanism being actuated by raising the window-sash, in combination with a fire-escape adapted to 115 be stored within said box when not in use, and which, upon allowing the bottom to fall, is automatically discharged into an operative position, reaching from the box to the ground, substantially as and for the purpose specified. 120

8. The combination of sheet-iron body C, re-enforced by angle-irons E F, hinged bottom K, hinged cover H, having extensions I', latch M, means to operate said latch and wire or chain N, substantially as and for the purpose 125 specified.

9. The combination of body C, hinged bottom K, latch M, spring M', lever P, and connecting mechanism whereby said lever operates said latch to free the bottom, substantially 130 as and for the purpose specified.

10. The combination of body C, hinged bot-

tom K, latch M, spring M', lever P, having stop p', hinged arm P², spring R, window-sash B, and connecting mechanism whereby said lever operates said latch to free the bottom, 5 substantially as and for the purpose specified.

11. The combination of body C, having slots D', hinged bottom K, hinged cover H, having extensions I', wire or chain N, and sliding

plates D², substantially as and for the purpose specified.

In testimony of which invention I hereunto set my hand.

HENRY W. LITTLEFIELD.
